FIG. 1

FIG. 2

FIG. 3

FIG. 4

FIG. 5

FIG. 1 is a perspective view of an electrical testing or sensing instrument embodying our design looking at the top and two sides thereof;

FIG. 2 is a top plan view taken from above as seen in FIG. 1;

FIG. 3 is a front elevational view;

FIG. 4 is a rear elevational view; and

FIG. 5 is a side elevational view.

The side opposite that illustrated in FIG. 5 is the same and the bottom is unornamented and, hence, these views are not illustrated.

We claim:

The ornamental design for an electrical testing or sensing instrument, substantially as shown and described.
